(57) **CLAIM**

The ornamental design for a salad cutter, as shown and described.

DESCRIPTION

FIG. 1 is a right, front perspective view of the salad cutter of the present invention;

FIG. 2 is a right side view thereof;

FIG. 3 is a left side view thereof;

FIG. 4 is a rear side view thereof;

FIG. 5 is a front side view thereof;

FIG. 6 is a top view thereof; and,

FIG. 7 is a bottom view thereof.

The broken lines shown in the drawings are for illustrative purposes only and form no part of the claimed design.
